Fig. 1.

UNITED STATES PATENT OFFICE.

JONATHAN D. FARR, OF MIDDLETON, GEORGIA.

FIRE-EXTINGUISHER.

1,026,856.

Specification of Letters Patent.

Patented May 21, 1912.

Application filed July 24, 1911. Serial No. 640,282.

To all whom it may concern:

Be it known that I, JONATHAN D. FARR, a citizen of the United States, residing at Middleton, in the county of Elbert and State of Georgia, have invented a new and useful Fire-Extinguisher, of which the following is a specification.

This invention relates to fire extinguishers.

10 The object of the invention is to provide a novel apparatus that shall be automatic in operation in the event of a fire; in which the distribution of the extinguishing fluid shall be accomplished in the most effective and certain manner; in which the discharge shall be utilized to rotate the container, thus to distribute the fluid over a large area, the container, through suitable mechanism, being caused, during rotation, to sound a continuous alarm so long as the apparatus is in operation, and in which all danger of failure of the apparatus to work in case of fire will positively be precluded.

With the above and other objects in view, 25 as will appear as the nature of the invention is better understood, the same consists in the novel construction and combination of parts of a fire extinguisher, as will be hereinafter fully described and claimed.

30 In the accompanying drawings, forming a part of this specification, and in which like characters of reference indicate corresponding parts, Figure 1 is a view in side elevation, partly in section, displaying the apparatus when not in action. Fig. 2 is a similar view of the apparatus when in action. Fig. 3 is a fragmentary detail view of a portion of the apparatus. Fig. 4 is a horizontal sectional view, taken on the line 35 4-4, Fig. 1. Fig. 5 is a side elevation of the weight arm and its holding line.

40 Referring to the drawings, 1 and 2 designate two hangers, which are supported from a suitable over-head support, such as a ceiling C.

45 Journaled in the lower ends of the hangers are the terminals 3 of a drop-shaft, secured to the center of the arch 4 of which, in any suitable manner, is a block 5 having formed therein a seat 6 to be engaged by a pivot or stud 7 carried by a trunnion 7^a arranged at the center of a bowed strap 8 that is secured in any manner to a cylindrical receptacle 9 which constitutes the container 50 for the extinguishing fluid, which in this instance consists of sodium bi-carbonate

designated S, and sulfuric acid contained in a flask F housed in an open-work holder or cage that depends from a head 11 that is screw-threaded into the upper end of the receptacle. This flask has a stopper of lead, glass or the like which will not adhere to the flask but will drop freely therefrom when the flask is inverted.

55 The receptacle may be made of any material, preferably one that is non-frangible such as enameled sheet iron, or any material that is suitable for the purpose. To the head 11, or to the receptacle, is secured a second bowed strap 12 carrying at its center a pivot or stud 13 that is designed to engage a socket or bearing in a block 14 secured to the upper horizontal member 15 of a frame, the side arms 16 of which are secured in any preferred manner to the arched shaft 4, as clearly shown in Fig. 1. The object for employing the sockets or bearings for the studs 6 and 13 is to reduce the friction between these parts to a minimum, as it is designed that when the receptacle is inverted, as shown in Fig. 2, escape of the carbonic acid gas generated by the action of the sulfuric acid on the sodium bi-carbonate will set up a back pressure which will cause the receptacle rapidly to 80 revolve, the escape taking place through discharge nozzles 16^a, arranged near the lower end of the receptacle when inverted and discharging respectively in an upward and outward, and downward and outward 85 direction relative thereto, so that the misty fluid will be caused to distribute over a relatively large area and thus secure the best results. In addition, the swinging motion imparted to the receptacle when it 90 drops from its non-active position shown in Fig. 1 to its active position in Fig. 2, will cause a further agitation of the chemicals, and thus accentuate the production of the gas as will be obvious. It is essential, in apparatus 95 of this character, that positively operating means be provided, whereby in the event of fire, that the extinguisher shall become operative when the heat reaches, say, 150° Fahrenheit, and to secure this result, there 100 is a shaft 17 provided, which is mounted in bearings formed adjacent to the upper ends of the hangers, those portions of the shaft that engage with the hangers being formed with knife-edge bearings, as shown 105 in Fig. 3, thus to reduce friction to a minimum, and to obviate any danger of the shaft 110

becoming rust-locked. The intermediate portion of the shaft carries a recessed lug or dog 18, into the recess of which fits a toe or catch 19 carried by the center portion 5 of the horizontal member 15 of the frame, the co-action between the parts being of loose character to prevent any possibility of binding. One end of the shaft 17 is provided with an arm 20 carrying adjacent to 10 its extremity a weight 21, the function of which is to turn the shaft 4 from the position shown in Fig. 1 to that shown in Fig. 2, which will operate to cause the dog to impart a lateral throw, through the medium 15 of the catch 19, to the receptacle supporting frame consisting of the members 15 and 16, and thus cause it to drop, whereupon the sulfuric acid will be discharged into the sodium bi-carbonate and start the generation 20 of carbonic acid gas.

The means for maintaining the weighted end of the shaft 4 in the position shown in Fig. 1 consists of fuse lines 22 made up of chains or wire connected by fusible links 25 22', said lines being connected to the arm 20, so that in the event that any one of the fusible links should melt, the weight will be released and thus trip the receptacle.

In order to cause the rotation of the receptacle, by the escape of the gas, to sound 30 an audible alarm, there are two gongs 23 provided, which are carried by a plate 24 secured to the angle band 25 of the shaft 4. These gongs are alternately engaged by a 35 hammer 26 that is carried by one end of an arm 27 the other end of which carries a finger 28. The arm 27 is pivotally connected with the upper end of a standard 29 secured to the shaft 4, and is free to vibrate easily 40 thereon, the finger 28 being arranged in the path of movement of a cam 30, carried by the trunnion 7^a that is designed to engage with the finger 28 as the receptacle rotates, and thus vibrate the arm 27 and effect the 45 sounding of one of the gongs, the hammer being brought into engagement with the other gong by a spring 31 carried by the shaft 4 and extending through the arm.

From the foregoing description it will be 50 seen that provision is made to insure the certain inversion of the receptacle containing the gas-forming chemicals in the event of fire, in a manner that will be certain of operation, and further, that by the manner 55 of supporting the receptacle, its rotation will be assured, so that the spraying or discharge of the misty gas will be most effective in results.

It is to be understood that the means here- 60 in shown for sounding the gongs is merely

illustrative of one form that may be employed, and therefore the invention is not to be limited thereto.

It is designed that the apparatus shall be made in neat and compact form, so that 65 when positioned upon a ceiling it will not present an unsightly appearance.

I claim:

1. A fire extinguisher including a tank mounted for swinging movement about an 70 axis extending transversely through one end portion thereof and for rotation about its longitudinal axis, and means for discharging the contents of the tank in jets to rotate the tank when swung to inverted position. 75

2. A fire extinguisher including a frame, a tank mounted for rotation in the frame about the longitudinal axis of the tank, said frame being arranged to swing about an axis extending transversely through one end 80 portion of the tank, suitable means for holding the tank normally in one position, said tank and frame being adapted to swing to inverted positions when released, and nozzles for directing jets upwardly and downwardly along lines receding from the tank when the tank is inverted, to rotate the tank. 85

3. A fire extinguisher comprising a hanger, a trip rod journaled therein and 90 provided intermediate of its ends with a dog and at one terminal with a weight, an oscillating shaft journaled in the lower ends of the hanger, a cylinder supported for rotary movements by the frame and by the 95 shaft and containing fire extinguishing chemicals, means carried by the frame to engage the dog to maintain the cylinder in upright position, and a discharge nozzle carried by the cylinder and operating to cause 100 rotation of the cylinder and thus the discharge of the contained chemicals over a large area when the cylinder is inverted.

4. A fire extinguisher including a tank mounted for swinging movement about an 105 axis extending transversely through one end portion thereof and for rotation about its longitudinal axis, and nozzles for directing the contents of the tank in jets upwardly and downwardly along lines receding from 110 the tank when the tank is inverted, to rotate the tank about its longitudinal axis.

In testimony that I claim the foregoing as my own, I have hereto affixed my signature in the presence of two witnesses.

JONATHAN D. FARR.
